(57) **CLAIM**

The ornamental design for a self propelled scooter, as shown and described.

DESCRIPTION

FIG. 1 is a right side elevational view of the self propelled scooter of the present invention showing my new design;

FIG. 2 is a top plan view thereof;

FIG. 3 is a left side elevational view thereof;

FIG. 4 is a bottom plan view thereof;

FIG. 5 is a front elevational view thereof; and

FIG. 6 is a rear elevational view thereof;

FIG. 7 is a right side perspective view of a second embodiment of the self propelled scooter of the present invention showing my new design;

FIG. 8 is a top plan view thereof;

FIG. 9 is a left side elevational view thereof;

FIG. 10 is a bottom plan view thereof;

FIG. 11 is a front elevational view thereof; and,

FIG. 12 is a rear elevational view thereof.
